UNITED STATES PATENT OFFICE.

EARL FORSTER, OF ROGERSTOWN, TEXAS.

DEVICE FOR GRINDING AND REMOVING THE VALVES OF EXPLOSIVE-ENGINES.

1,158,796.

Specification of Letters Patent.

Patented Nov. 2, 1915.

Application filed August 24, 1915. Serial No. 47,163.

To all whom it may concern:

Be it known that I, EARL FORSTER, a citizen of the United States, residing at Rogers-
town, in the county of Ochiltree, State of
Texas, have invented certain new and useful
Improvements in Devices for Grinding and
Removing the Valves of Explosive-
Engines; and I do hereby declare the following
to be a full, clear, and exact description
of the invention, such as will enable
others skilled in the art to which it appertains
to make and use the same.

This invention relates to devices for
grinding and removing the valves of explosive
engines.

The object of the invention is to provide
a device of the character named which will
be simple in construction, easily operated,
efficient in action, and which can be manufactured
at a comparatively small cost.

With the above and other objects in view
the invention consists in the details of construction
and in the arrangement and combination
of parts to be hereinafter more
fully described and particularly pointed out
in the appended claim.

In describing the invention in detail reference
will be had to the accompanying drawings
wherein like characters of reference
denote corresponding parts in the several
views, and in which—

Figure 1 is a view showing the improved
device operatively applied; Fig. 2, a vertical
section of the device; Fig. 3, a plan
view of the device; Fig. 4, a section on the
line 4—4 of Fig. 2, and Fig. 5, a perspective
view of the valve gripping element.

Referring to the drawings 10 indicates
an explosive engine, 11 a valve associated
therewith and including a stem 12 having
a transverse pin 13. The valve 11 is normally
held to its seat by a spring 14 bearing
at one end against the pin 13 and at its
other end against the engine 10 all in the
usual and well known manner.

The improved device comprises a bar 15
having fixed thereto adjacent one end an
arm 16, said arm being disposed at right
angles to the bar 15. Slidably engaged on
the arm 16 is a forked member 17 including
arms 18 and 19. Rotatably mounted in the
bar 15 and extending parallel to the arm 16
is a lead screw 20 provided with wings 21
for convenience in rotating same. This lead

screw 20 is threaded in an opening 22 in
the member 17 whereby rotation of the
screw 20 will move the member 17 longitudinally
of the arm 16. Rotatably mounted
on the bar 15 are meshing gears 23 and
24, the hub of the former being extended to
form a chuck 25. Fixed to the hub of the
gear 24 is a handle 26 whereby the gear 24
may be conveniently rotated for the purpose
of rotating the gear 23 and the chuck
25. Removably engaged in the chuck is a
valve gripping tool 27 including spaced
projections 28 adapted to seat in recesses 29
in the valve 11 and thus interlock the tool
and valve so that rotation of the tool will
effect rotation of the valve.

In the use of the device the tool 27 is applied
to the chuck 25 and the projections 28
engaged in respective recesses 29. The fork
member 17 is forced beneath the spring 14
and above the pin 13 with its arms in embracing
relation to the stem 12. The screw
20 is then rotated to raise the member 17
on the arm 16 and thus relieve the valve 11
from the influence of the spring 14. The
gear 23 is then rotated and such rotation
will be transmitted to the valve 11 to effect
grinding of the valve. It will of course be
obvious that the spring 14 will produce the
desired pressure on the valve during the
operation of grinding. It will be further
obvious that the device can be utilized with
equal facility to effect removal of the
valve when desired.

What is claimed is:—

A device of the class described comprising
a bar, an arm carried by said bar adjacent
one end of the latter, said arm being
disposed at right angles to the bar, a forked
member slidably mounted on the arm and
disposed in a plane parallel to the plane of
the bar, a lead screw rotatably mounted in
the bar and having threaded engagement
with the forked member whereby rotation
of the screw will move said member longitudinally
of the arm, a valve engaging tool
rotatably mounted on the bar, and means
for rotating said tool.

In testimony whereof, I affix my signature,
in the presence of two witnesses.

EARL FORSTER.
